UNITED STATES PATENT OFFICE.

EDWARD H. CLARK, OF WINNIPEG, MANITOBA, CANADA.

COMBINED PEN AND BLOTTER.

1,190,983.

Specification of Letters Patent. Patented July 11, 1916.

Application filed June 23, 1915. Serial No. 35,886.

To all whom it may concern:

Be it known that I, EDWARD H. CLARK, a subject of the King of Great Britain, residing at Winnipeg, in the Province of 5 Manitoba and Dominion of Canada, have invented new and useful Improvements in Combined Pens and Blotters, of which the following is a specification.

An object of the invention is to provide 10 a pen and a blotter associated with the pen and whereby the blotter can be conveniently used to blot the writing made by the pen.

The invention comprehends, among other 15 features, the provision of a pen carrying a blotter, with the pen constituting the handle or holder for the blotter, the blotter being normally invisible when the pen is in use but adapted to be exposed for blotting the 20 writing made by the pen.

In the further disclosure of the invention reference is to be had to the accompanying drawings, constituting a part of this specification, in which similar characters of reference denote corresponding parts in all the 25 views, and in which:

Figure 1 is a fragmentary vertical longitudinal sectional view taken through a fountain pen showing my invention; Fig. 30 2 is a similar view with the sheath shown removed; and Fig. 3 is a vertical transverse 35 sectional view taken on the line 3-3 in Fig. 1.

Referring more particularly to the views, 40 the pen is indicated by the numeral 10 and includes the usual barrel 11 which, near its inner end, is slightly enlarged to form an annular seat or abutment 12. A substantially cylindrical blotter 13 closely encircles the barrel 11 and in cross section the 45 diameter of the blotter 13 is slightly greater than the diameter of the inner end of the barrel 11 adjacent the reduced portion thereon. The blotter 13 has its outer end bent inwardly or cupped, as shown at 14, a suitable headed screw 15 being arranged to screw into a threaded opening in the substantially solid outer end of the barrel and wedge the inwardly bent or cupped portion 50 of the blotter between the barrel and the head of the screw, furthermore, carrying a spring-like catch 16 adapted to receive a projecting member 17 extending from the inner end of a sheath 18, which is adapted

to fit over the barrel and inclose the blotter, the free end of the sheath when in this position being in juxtaposition with relation to the seat or abutment 12, and it will be seen, with reference to Fig. 1 in the drawing that the member 17 will engage 55 with the catch 16 and the sheath will thus be held against accidental removal and will entirely inclose the blotter.

In the use of the pen, after the writing has been produced in the usual manner, 60 the sheath is removed from the barrel by pulling outwardly thereon, thus exposing the circular or cylindrical blotter 13 held upon the barrel by having its inwardly bent portion secured to the screw 15. The 65 pen is now laid upon the paper having the writing thereon and with the hand rolled or advanced over the paper so that the projecting cylindrical surface of the blotter 13 will come in rotary contact with the portion of the paper having the writing thereon and blot the writing.

With a device of the character described 70 it will be clearly seen that there is provided a structure that will have a compact 75 appearance and in which the blotter will at all times form a part of the pen, the blotter, when it becomes worn out being removed from its encircling relation to the barrel to permit of inserting a new blotter 80 85 in its place.

The pen carries the usual closure 19 which when the pen is not in use has inserted 90 therein the enlarged end of the barrel 11 and the free end of the sheath 18 in the usual manner.

Having thus described the invention what is claimed as new is:

In combination with the body of a pen, 95 a blotter encircling the body, a screw fitting into the body and engaging the blotter to hold the same against removal, a sheath for the blotter and encircling the body of the pen, a catch on the screw, and a projection on the sheath engageable with the catch to hold the sheath against accidental removal.

In testimony whereof I affix my signature in presence of two witnesses.

EDWARD CLARK.
